STEAM IRON HANDLE

John E. Reed, Glen Ellyn, Ill., assignor to Sunbeam Corporation, Chicago, Ill., a corporation of Illinois

Filed June 4, 1963, Ser. No. 75,211

Term of patent 14 years

(Cl. D49—6)

FIG. 1 is a perspective view of a steam iron handle embodying my new design;

FIG. 2 is a front elevational view thereof;

FIG. 3 is a rear elevational view thereof;

FIG. 4 is a left side elevational view thereof; and

FIG. 5 is a top plan view thereof.

The broken lines shown in FIG. 1 indicating the base portion are for illustrative purposes only.

The dominate features of my design reside in the portions shown in full lines.

I claim:

The ornamental design for a steam iron handle, as shown and described.
